DETORSION SHOE

Emil Lattemann, Waldfischbach/Palatinate,
GermanyApplication June 2, 1938, Serial No. 211,435
In Germany August 5, 1937

7 Claims. (Cl. 36—71)

- The axial position for shoes made on a last, emanating from Professor von Meyer and which was formerly generally employed has been abandoned in the last decades by the industry and shoemaking trade after, particularly doctors, such as Dr. Schanz Officer of Health of Dresden, have upheld the view that besides feet corresponding to the Meyer fundamental or axial position, also feet with a so-called straight axial position exist.
- 5 A centre line according to the Meyer fundamental position extends from the middle of the heel accurately through the middle of the big toe, whereas according to Schanz the centre line passes accurately from the middle of the heel between the second and third toes. The change 10 in the position of the big toe, especially the cause for crooked toe, was attributed partly to too pointed footwear and partly to progressive splaying of the foot formation.
- 15 20 In spite of the many rules for the treatment of such feet no method has been devised so far which enables at least the changed yet still normal foot to be brought to a normal development. It is generally agreed that, when walking, first 25 the inner tuberosity of the oscalsis is first brought to bear, whereupon the weight of the body is gradually supported by the outer edge of the foot up to the outer ball and thence to the inner ball, being finally transferred to the big toe.
- 30 35 The so-called wringing of the foot when walking has been ascertained by many doctors. In order to attain such a development of the foot when walking with factory-made shoes, many supports have been proposed, by which the foot is given an inclined position that is the so-called first phase from the oscalsis up to the outer edge of the foot. In the majority of cases, however, difficulties occur from this point, namely in order to obtain the change over from the outer ball on to the inner ball as second phase, in order to then carry out the third phase of the development of the foot over the big toe, which is only possible from the second phase.
- 40 45 It has been proposed to obtain this heel guiding by supporting the sustentaculum tali as suggested by the weak instep support described in German Patent No. 522,874, as this ensures the correct position of the oscalsis. On the other hand, no shoe exists to-day which allows the front portion of the foot to tread so straightly as it does in soft sandy soil, namely the soft inner ball to become more deeply embedded than the outer ball, as according to the normal foot development the little toe ball only serves for 50 steadying while, as compared with the big toe 55
- ball, the inner ball carries the whole load. For this purpose nature has provided the inner ball with sesamoid bones. If by wrongly shaped footwear the inner ball can scarcely work and if then the main load is placed on the outer ball 5 during the bending of the foot, the foot can only function in an imperfect manner, this becoming apparent by the treading over of the shoes. On the other hand, a changed axis position in no way re-establishes the performance of the foot 10 and consequently provision must be made to ensure, that the second phase of the foot, that is the changing over from the outer ball to the inner ball, is not rendered more difficult but facilitated.
- 15 The object of the invention is, to attain the correct development of the foot, that is the wringing in the above described three phases, by a novel construction of shoe, especially by a novel construction of the insole.
- 20 It is known to provide transverse slits in the insoles of footwear and such transverse slits have even been arranged in the longitudinal direction in order to thereby obtain greater flexibility. Furthermore, the bent up flaps of the insole 25 have also been provided with incisions to cause them to fit more snugly on the upper. On the other hand, insoles have been proposed which are incised all around their edge so as to ensure good bearing against the upper when bending up. 30 Finally, domed supports are known which are provided with transverse slits.
- 35 As compared herewith the invention consists in that the insole is provided only at the outer ball with transverse slits converging from the 35 outer edge towards the inner ball.
- 40 By this novel construction, and particularly by the combined application of a slit outer ball wedge tapering towards the edge of the inner ball, a normal development of the foot in the above described three phases is obtained when walking in that:
- 45 1. A straight position of the front portion of the foot on the ground is obtained, in that a minimum outer edge wedge of 2 to 3 mms. is fitted in each shoe.
- 50 2. This wedge and the insole above the same are made extremely flexible precisely at the outer ball effecting the second phase of the development that is the change over from the outer to 50 the inner side.
- 55 3. The shoe waist is made as pliable as possible from the middle up to the root of the ball and
4. Absolutely reliable heel position is ensured 55

by fitting a weak instep support particularly under the sustentaculum tali.

The known wedges, which have been arranged in various shapes, in different positions and in different lengths in shoes, in order to prevent treading over, cannot attain this object. By the employment of such wedges only a thickening of the outer edge and consequently a board-like stiffening is attained, which renders impossible a change over from the outer ball to the inner when walking.

The invention can be carried out in various ways. Two embodiments will be hereinafter described with reference to the accompanying drawings, in which:

Fig. 1 shows in top plan view an insole with wedge placed thereunder,

Fig. 2 is a longitudinal section through a sole of a shoe,

Fig. 3 shows the outer sole in top plan view with the wedge after removal of the insole,

Fig. 4 is a section on line III—III of Fig. 1,

Fig. 5 shows a modified form of construction of a shoe in longitudinal section,

Fig. 6 is a top plan view of Fig. 5,

Fig. 7 is a section on line VII—VII of Fig. 6.

Fig. 1 shows that the foot, commencing from the setting down point *a* of the heel develops in the direction of phase 1, then changes over from the small toe ball from the outer side towards the inner side in the direction of the arrow 2 as second phase, and finally rolls over the big toe ball in the direction of the arrow 3.

In order to attain this, a straight position of the front portion of the foot on the ground is ensured by employing an outer wedge *b* having only a slight taper from about 2 to 3 mms., and which is arranged under the insole *c* at the front merely on the outer ball in inward direction. The insole *c* is provided only on the outer ball with transverse preferably fan shaped slits *e* converging from the outer edge *d* up to the inner ball. The slits *e* extending almost across the entire width of the insole at the outer ball portion register with the slits *f* in the wedge *b* tapering from the outer ball towards the edge of the inner ball. The slits therefore register accurately, the wedge extends approximately from the transition from the waist to the outer ball up to almost the point of the shoe. The wedge tapers to a sharp point at a distance of about 1 cm. from the inner edge, as shown in Fig. 4 of the drawings.

A support *g* serving as weak instep support is arranged in the shoe under the oscalsis on the inner edge. The shoe is further constructed in its arch preferably as a freely oscillating joint.

By this novel construction of the insole with the slit thin wedge thereunder an extremely high degree of flexibility is imparted to the insole while at the same time giving the front portion of the foot an inclined position from the outer towards the inner side. The wedge may be rigidly connected with the insole. In any case, as the slits in the wedge and insole accurately register in equal lengths a kind of roller blind is formed. Thus, an exceptionally favorable development of the foot is attained especially from the outer to the inner side at the outer ball, that is the second phase of the walking movement is facilitated.

The insole with slits is preferably provided, after the stitching, with a cover sole which is formed by a thin, soft covering layer *h* of chrome-tanned upper leather or similar soft material

extending from the tip to the waist and which is intimately connected with the front portion of the insole by sticking and pressing. Thus, the formation of a kind of roller blind with the members of the insole formed by the slitting is facilitated.

Provided the movability of the sole from the middle of the waist up to the root of the ball is ensured, the rear portion of the foot is brought, when walking, into supination by a weak instep support and the front portion of the foot into pronation.

This effect is increased if, as weak instep support (Fig. 5), a support *k* is used exclusively under the sustentaculum tali *i* of the known oscalsis spur on the inner side of the foot, this support being preferably adapted to the actual conditions as a wedge as regards varying thickness. Furthermore, the waist is kept flexible from the middle between the heel breast *l* and the beginning of the ball by fitting at the heel under the oscalsis a hard, strong steel spring *m* which extends from the middle of the heel bed only to almost the middle of the waist. The portion of the waist *n* between the end of the steel spring and the transition to the ball is filled with composition.

This relatively short steel spring is fitted in the heel or rigidly connected therewith so that the spring can be regarded as forming part of the heel portion. The spring has for its object to support the weak instep support lying over the inner heel edge and the outer edge wedge preferably in conjunction with a pasteboard stiffener so that the base for the oscalsis may be called independent and absolutely solid.

For the purpose of forming an indented heel mould a heel wedge *o* may be arranged in known manner on the outer edge. The technical difficulty arising when tacking the slit insole and wedge can be surmounted by placing a strip of paper or the like on the under side of the insole over the slits during the tacking. Care must be taken, when filling, to see that the composition does not penetrate between the members formed by the slits *f* in the wedge and by the slits *e* in the insole and there form a stiffening.

The fixation may be effected in various ways, for example the waist spring can be riveted to the insole which in turn is held on the heel by 50 nails which hold together the insole, outer sole and heel. If desired, separate fixing staples may be provided.

However, it is also possible to arrange the waist spring on the inner side of the outer sole and to attach it in some way to the outer sole and the heel.

It is evident that a separate waist stiffener of paste board or the like can be arranged under the insole in known manner and extend from the rear heel edge in to the waist.

Figs. 6 and 7 show that in the arrangement of a splay foot support *p* constructed in known manner the slit insole with the slit outer wedge is thickened at its outer edge by an amount equal to the thickness of the splay foot wedge.

The base produced according to the invention enables an inclining of the oscalsis from the depth of the heel bed and the returning of the foot into its original position and, in conjunction with the flexible front portion of the foot twisted relatively to the rear portion of the foot by the wedge, an oscillating, soft waist middle portion and consequently a movability and maintaining of the fundamental position are attained which

could not be attained with the known shoes, as the disadvantages of the hardness of the flat and hard paving are rendered harmless by the above described novel construction and arrangement of the support.

5 I claim:

1. In an orthopedic shoe, an insole provided with slits extending almost across the entire width at the outer ball portion and an outer wedge tapering from the waist transition portion to the outer ball almost up to the point on the one hand and to the inner ball edge on the other hand, said wedge having slits corresponding and registering with those in the insole and lowering the inner ball relatively to the outer ball.
- 10 2. In an orthopedic shoe, an insole provided with slits extending almost across the entire width at the outer ball portion and an outer wedge 2.5 to 6 mms. in thickness tapering to a sharp edge at a distance of 1 cm. from the inner edge of the insole, said wedge having slits corresponding and registering with those in the insole and lowering the inner ball relatively to the outer ball.
- 15 3. In an orthopedic shoe an inner sole provided on the outer ball portion with transverse slits converging from and through the outer edge towards the inner ball portion a soft covering layer of yielding material extending over the insole from the point to the beginning of the waist portion and intimately connected with the front portion of the insole by sticking and pressing to form a flexible tie-between and with the members formed in the insole.
- 20
- 25
- 30

4. In an orthopedic shoe an insole provided with slits extending almost across the entire width at the outer ball portion, an outer wedge having slits corresponding and registering with those in the insole and lowering the inner ball relatively to the outer ball, and a splay foot support on said insole, said insole being thickened by said outer wedge to a thickness equal to that of the support.

5. In an orthopedic shoe an insole provided with slits extending almost across the entire width at the outer ball portion, an outer wedge having slits corresponding and registering with those in the insole and lowering the inner ball relatively to the outer ball, and a waist stiffening comprising a hard steel spring extending from the heel bed about 4 to 5 cms. into the waist over the heel breast portion but considerably shorter than the ordinary waist spring.

6. The shoe of claim 3, characterized by having the slits formed with side edges converging from the outer edge of the sole to their inner ends.

7. In an orthopedic shoe, a slit flexible inner sole wherein the sole has transverse incisions characterized in that the said transverse incisions form slits extending through said inner sole and solely formed in the outer ball portion of said inner sole, said slits each tapering from the outer edge of the inner sole to the inner ball portion of the said sole.
